UNITED STATES PATENT OFFICE.

HARRY N. COPP, OF SWAMPSCOTT, MASSACHUSETTS, ASSIGNOR TO UNITED SHOE MACHINERY CORPORATION, OF PATERSON, NEW JERSEY, A CORPORATION OF NEW JERSEY.

HEEL-MAKING MACHINE.

Application filed November 15, 1920. Serial No. 424,219.

To all whom it may concern:

Be it known that I, HARRY N. COPP, a citizen of the United States, and resident of Swampscott, in the county of Essex and 5 State of Massachusetts, have invented certain Improvements in Heel-Making Machines, of which the following description, in connection with the accompanying drawings, is a specification, like reference characters on the drawings indicating like parts in the several figures.

This invention relates to heel making machines and is herein described and illustrated as embodied in a machine for producing, 15 practically automatically, heels comprising pieced and whole lifts in combination.

Heels of the character described have been produced commercially for many years by cutting and assembling lifts by hand into 20 a die supported upon a bench with its cutting edge uppermost. This is known in the trade as the Haverhill die method.

Any hand method of producing articles made in such quantities as heels must, of 25 necessity, be slow and involve a relatively high labor cost. The object of the present invention is to produce a machine for making heels, similar to those heretofore made by the Haverhill die process, in an expeditious manner, greatly increasing the production of an operative and correspondingly reducing the labor cost per unit of product.

An important feature of the invention contributing to this end consists in means for 35 removing a plurality of pieces of lift material from a support upon which they are assembled with their edges abutting, transferring them to, and cutting them into a die. By a sufficient number of repetitions of this 40 operation the desired number of complete lifts is accumulated in the die. In the preferred form of the invention nailing mechanism is also provided for securing the lifts together while they are in the die. In the 45 illustrative embodiment of the invention herein shown the lifts are automatically nailed together as they are assembled in the die and the heel blank is automatically ejected from the die.

50 Inasmuch as heels of the type above described usually contain one or more whole lifts, in combination with the pieced lifts, a further feature of the invention consists in the combination with the mechanism above mentioned of mechanism operating in

proper time relation thereto for producing from a magazine and inserting or cutting into the die one or more lifts which may or may not have previously been died out to approximately their ultimate size and shape. 60

These and other features of utility in the invention will be better understood and appreciated from reading the following detailed description of one embodiment thereof in combination with the accompanying 65 drawings, in which—

Figure 1 is a side elevation of the illustrative machine, parts of the base being broken away to reveal the interior mechanism; 70

Fig. 2 is a view partly in elevation and partly on a section, taken substantially at right angles to Fig. 1;

Fig. 3 is a plan view of the machine;

Fig. 4 is a view illustrating a detail of the 75 lift picking mechanism for whole lifts;

Fig. 5 is a view showing pieces of heel lift stock fitted together, ready to be operated upon by the machine;

Fig. 6 is a perspective view of a heel produced by the machine; and 80

Fig. 7 is a view of a detail of the heel blank releasing mechanism.

Referring now to the drawings, 10 indicates a base or frame of suitable design and construction to support the operating mechanisms of the machine. A bracket 12 is bolted to the machine base and supports a stationary, upwardly facing cutting die 14 into which the heel lifts are cut and assembled. Two cutting plates 16, 18, operating alternatively to cut lifts into the die 14 are actuated by mechanism presently to be described. The cutting plates 16, 18 are carried respectively by arms 20, 22 projecting horizontally, at right angles to each other, from a swinging head 24 carried by the upper end of a vertically reciprocable and horizontally oscillatory plunger 26 guided for movement in vertical bearings in the base 10. 90

A bracket 28 is gibbed to the front of the base 10 and may be adjusted vertically by means of a screw 30 upon which it is supported. The bracket 28 carries a table 32 having a spindle 34 extending downwardly into a suitable bore in an enlarged cylindrical portion 36 of the bracket. The lower end of the spindle 34 rests upon a substantial spring 38, the position or tension of which may be adjusted by a screw 40. A detach- 100

able plate 42 is secured by screws 44 in a recess in the top of the table 32, with the upper surface of the plate substantially flush with the surface of the table. The plate 42 has marked upon it an outline 46 identical with the outline of the cutting edge of the die 14. It is intended that plates be provided with outlines corresponding to all the dies with which the machine is equipped and, the outside dimensions of all the plates being identical, they are readily interchangeable.

The end of the arm 20 is hollowed out to receive a needle plate 48 which is provided with a plurality of pointed needles 50 projecting through holes in the cutting plate 16. The needle plate 48 is backed up by a spring 52 which surrounds a spindle 54 projecting upwardly from the needle plate and pivoted at 56 to a lever 58. The lever 58 is pivoted to the head at 60 and is pivotally connected, between its ends, to a vertically reciprocable actuating rod 62, the lower end of which is arranged to engage, at certain times, a stationary lug 64 projecting from the base member 10.

The outer end of the arm 22 is provided with an internally threaded, vertical opening in which is adjustably secured a supporting member 66 for the cutting plate 18. The supporting member 66 also carries a plurality of fingers 68 arranged to engage the edges of a lift or piece of lift stock and pick it up. The lower ends of the fingers 68 are curved outwardly, as shown at 70, and each finger is pivotally supported in a block 72 arranged for radial adjustment with respect to the member 66 by means of a screw and slot connection 74. A spring 76 tends constantly to swing the finger 68 inwardly about its pivot and outward movement of the finger against the tension of the spring is effected by a rod 78 having at its lower end a head 80 arranged to engage arms 82 which project inwardly, substantially at right angles, from the upper ends of all the fingers 68. The upper end of the rod 78 is pivotally connected to one end of a lever 84 fulcrumed at 86 in a bracket 88 carried by the arm 22, the opposite end of the lever 84 being pivoted to a vertically reciprocable rod 90. The lower end of the rod 90 carries a pivoted dog 92, shown in Fig. 7, which may swing freely in one direction with respect to the rod, but not in the other. The lower end of the dog is arranged to engage a stationary, inclined cam face 94 as the arm 22 is swung horizontally over the cam.

A stationary table 98, at the side of the machine opposite to the table 32, supports a blank magazine 100 and mechanism for feeding blanks from the lower end thereof. The feeding mechanism consists of a horizontally reciprocable pusher 102 connected by a link 104 to a bell crank lever 106 which is rocked

about a stationary pivot 108 by a rod 110 connected to a cam lever 112, the operating means for which will presently be described.

Power for driving the machine may be derived from any suitable source such, for example, as a belt 113 driving a pulley 114 mounted upon the main driving shaft 116. The opposite end of the driving shaft 116 carries a crank 118 which is operatively connected, through a connecting rod 120 and a rotary thrust bearing 122 to a heavy screw 124. The screw 124 is threaded into the lower end of the plunger 26 and the upper end of the screw is connected by a rod 126 to an adjusting hand wheel 128 at the top of the machine. It will be apparent that, with this construction, the plunger and the arms 20, 22 carried thereby, will be reciprocated vertically as the driving shaft 116 rotates.

The driving shaft 116 is connected by gearing 130 to a shaft 132 carrying a worm 134 which meshes with a worm wheel 136 upon a cam shaft 138. The cam shaft 138 carries two cams, the center lines of which are indicated in Fig. 1 by dotted lines 140 and 142.

The cam 140 is engaged by a cam roll 144 upon the lever 112 which is mounted to oscillate about a stationary pivot 146. The cam 142 engages a cam roll 148 upon a lever 150 movable about a stationary pivot 152 and connected by a rod 154 to one arm 156 of a bell crank lever, the opposite arm 158 of which has, at its upper end, a gear segment 160. The gear segment 160 meshes with corresponding gear teeth upon a sleeve 162 which is rotatable in the base 10 but is restrained from vertical movement therein. A splined connection 164 between the sleeve 162 and the plunger 26 permits the plunger to reciprocate vertically through the sleeve but causes the plunger to partake of any horizontal rotary movement of the sleeve.

It will be apparent from an inspection of Fig. 1 that the cam 142, which oscillates the plunger 26 and swings the arms 20, 22 horizontally, has three rises; while the cam 140, which is fixed with relation to the cam 142 on the shaft 138 and which operates the blank feeding pusher 102, has but one rise. Consequently three horizontal oscillations of the head 24 and arms 20, 22 will occur for each reciprocation of the pusher 102. By this organization the machine is adapted to produce the heel blank shown in Fig. 6, consisting of two pieced lifts and two whole lifts. The relative timing of the driving shaft 116 and the cam shaft 138 is such that the shaft 116 makes three revolutions to each revolution of the cam shaft; the plunger 26 is, therefore, reciprocated vertically after each of its horizontal oscillations.

Any suitable clutch and brake mechanism 170, controlled by a treadle 172, may be

employed to control the application of power to the machine.

For the purpose of nailing the lifts together as they are cut into the die 14, nail drivers 174 are provided. The drivers 174 are mounted in a driver head 176 located within the die 14 and normally stationary but adjustable vertically by a hand wheel 178 engaging a threaded tube 180 extending downwardly from the head 176. The drivers 174 are surrounded by springs 182 which support an ejector plate 184 having nail tubes 186 surrounding the drivers. An ejector rod 188, provided with an adjusting turn buckle 190 and operated by a rocker arm 192, provides for imparting a positive ejecting movement to the plate 184. The arm 192 is secured to a rocker shaft 194 having a short arm 196 arranged to be engaged by a pin 198 upon the side of the worm gear 136.

The operation of the machine is as follows: Let it be assumed that the magazine 100 contains a supply of whole lifts or pieces from which whole lifts may be cut. Preferably, the pieces in the magazine 100 will be of the same shape as the die 14 and of the same size as the die, or only slightly larger. As shown in Fig. 1, the lower end 25 of the magazine is spaced sufficiently above the table 98 to permit two lifts to be pushed out at a time and the pusher 102 is sufficiently thick to engage two lifts at a time.

Pieces of scrap leather *a*, *b*, *c*, the edges 30 of which have been straightened, are fitted together, with their edges abutting, on the table 32, a sufficient number of pieces being used to cover the outline 46. The head 24 now swings to a position in which the arm 20 is over the table 32, and the plunger 26 moves downwardly until the plate 16 is pressed upon the pieces *a*, *b*, *c*, the needles 35 entering the said pieces and the spring 38 yielding, if necessary, to accommodate the thickness of the stock and the fixed stroke of the plunger 26. The plunger 26 next rises, the pieces *a*, *b*, *c* being picked up by the needles and their relation to each 40 other being preserved. The arm 20 now swings through 90 degrees to a position over the cutting die 14, the arm 22 at the same time swinging to a position over the table 98 but, inasmuch as no lifts have yet been fed from the magazine 100, the finger 68 45 will find nothing to pick up. The plunger 26 descends, causing the stock held against the underside of the cutting plate 16 to be cut into the die 14, thus cutting a complete pieced lift into the die at a single stroke.

As the head 24 descends to cut the pieces 50 into the die 14 the lower end of the rod 62 will engage the projection 64, causing the pins 55 to be withdrawn from the stock and avoiding any danger of their removing the lift from the die. The plunger 26 rises and

the arm 20 again swings to a position over the table 32, upon which, in the meantime, another group of pieces *a*, *b*, *c* has been arranged to cover the outline 46. The plunger 55 descends, the pieces are picked up as before, carried to a position over the die 14 and cut into the die. Upon this swinging movement of the arm 20 to a position over the die, and the arm 22 to a position over the table 98, the pusher 102 is actuated to 60 push two lifts from the magazine 100 out upon the table 98 into a position where they will be engaged by the fingers 68 as the plunger 26 descends to cut the second pieced lift into the die. The fingers 68 are pressed by the spring 76 against the edges of the lifts with sufficient force to pick up the pair of whole lifts when the plunger 26 again rises and when the head 24 again 65 swings to position cutting plate 18 over the die 14 and the plate 16 over the table 32 the two lifts held in the fingers 68 are carried to a position over the die. The next descent of the plunger 26 causes these lifts to be pressed or cut into the die on top of the two pieced lifts already therein.

As lifts are successively cut into the die, as above described, the plate 184 yields, the lifts being forced upon the nails contained in the tubes 186. As the head 24 rises after the pair of whole lifts is pressed into the die, the pin 198 engages the lever arm 196, causing the rod 188 to engage the ejector plate 184 and positively eject the heel from the die. This occurs simultaneously with the upward movement of the fingers 68 and, at the end of such movement, the plate 184 is flush with the top of the die, the heel being held by the fingers 68. As the head 24 again swings, the dog 92, at the lower end of the rod 90, rides over the cam 94, causing the fingers to release the heel and drop it into a discharge chute 200. During the movement of the arm 22 in the reverse direction the dog 92 swings idly over the cam, avoiding the release from the fingers 68 of lifts being carried thereby from the table 98 to the die 14.

The scrap resulting from the cutting operations falls into a receptacle surrounding the die 14 and is discharged by a chute 202.

The series of operations above described is repeated indefinitely, producing heels at a very rapid rate compared with the common method of cutting them into a Haverhill die by hand.

A valuable advantage of the present invention, as compared with other power operated die cutting machines is that the operative, in handling the pieces of stock, is never required to place his hands near the cutting die and thus the danger of mutilation of the fingers, which is a drawback to most power-operated die cutting machines, is eliminated. Furthermore, a

complete lift is produced at each cutting stroke of the machine, in contra-distinction to the practice of cutting one piece at a time into the die as is customary in 5 the methods heretofore used.

Having described the invention, what is new and desired to be secured by Letters Patent is:

1. In a machine of the class described, the 10 combination of a lift cutting die, a support upon which a plurality of pieces of stock may be arranged with their edges abutting, and means for removing said pieces from the support and transferring 15 them to the die.

2. In a machine of the class described, the combination of a lift cutting die, a support upon which a plurality of pieces of stock may be arranged with their edges abutting, 20 and means for removing said pieces from the support and thereafter cutting them into the die.

3. In a machine of the class described, the combination of a lift cutting die, a support 25 upon which a plurality of pieces of stock may be arranged with their edges abutting, and means for removing all of said pieces simultaneously from the support and thereafter cutting them into the die.

30 4. In a machine of the class described, the combination of a lift cutting die, a support upon which a plurality of pieces of stock may be arranged with their edges abutting, and means for picking up said 35 pieces, maintaining their abutting relationship, and cutting them simultaneously into the die.

45 5. In a machine of the class described, the combination of a lift cutting die, a support for lift stock, and a cutting plate movable alternately between positions in which it is in register respectively with the support and the die, said plate being provided with means for picking up stock from the support.

50 6. In a heel making machine, the combination of a lift cutting die, a support upon which a plurality of small pieces of stock may be assembled with their edges abutting, a cutting plate mounted to oscillate from a position over the support to a position over the die, and needles constructed and arranged to be projected through the plate to pick up the pieces of stock and hold them 55 against the plate while the latter is moving from the support to the die.

60 7. In a heel making machine, the combination of a lift cutting die, a plurality of supports for pieces of lift stock, a plurality of cutting plates movable alternately into register with the die and with the respective stock supports, and means associated with each cutting plate for picking up stock from one of the supports.

65 8. In a heel making machine, the combina-

tion of a stationary lift cutting die, a vertically reciprocable, oscillatory head, a pair of arms projecting from the head at right angles to each other, a pair of oppositely disposed lift stock supports, cutting plates 70 carried by said arms, and means for oscillating the head to move the cutting plates alternately into register with the die and with the respective supports.

9. In a heel making machine, the combination of a lift cutting die, a support for lift stock, a cutting plate movable alternately between a position in which it is in register with the die and a position in which it is 75 in register with the support, stock holding 80 means associated with the cutting plate, and an ejector co-operating with the die to eject a cut blank from the die and insert it in the holding means.

10. In a heel machine, the combination of 85 an upwardly facing lift cutting die, a lift carrier movable over the die, and means for forcing lifts upwardly out of the die into the carrier.

11. In a heel making machine, the combination of a lift cutting die, a support 90 upon which pieces of lift stock sufficient to produce a complete lift may be assembled with their edges abutting, a magazine for whole lift pieces, means for feeding pieces 95 from the magazine, and means for transferring and cutting into the die first assemblages of pieces to produce pieced lifts and then pieces to produce whole lifts.

12. In a heel making machine, the combination of a lift cutting die, a reciprocable, oscillating head carrying a pair of arms arranged at right angles to each other, cutting plates disposed upon the arms to be brought alternately into register with the 105 die by the oscillation of the head, and power operated means for alternately reciprocating the head to move a cutting plate into cutting engagement with the die and oscillating the head to move the other cutting plate into 110 register with the die.

13. In a machine of the class described, the combination of a lift receptacle, reciprocating means for pressing lifts into the receptacle, a stock magazine, means for feeding pieces of stock from the magazine, an actuator for the feeding means, and means for reciprocating said pressing means a plurality of times for each operation of the actuator for the feeding means. 115

14. In a heel making machine, the combination of means for cutting a pieced lift from heel stock, and means for assembling with the said lift another lift produced outside of the machine. 120

15. In a heel making machine, the combination of mechanism for cutting scrap material into a pieced heel lift, and means for assembling with the pieced lift a whole lift produced outside of the machine. 125

16. In a heel machine, the combination of die, feeding means for feeding pieces of stock from the magazine to a predetermined position, and means for transferring the pieces from said position to a position in register with the die. 10

5 die.

17. In a heel machine, the combination of a lift cutting die, a magazine for holding pieces of lift stock of the same shape as the

In testimony whereof I have signed my name to this specification.

HARRY N. COPP.
